FIREARM

Carl G. Swebilius, New Haven, Conn.

Application November 23, 1932, Serial No. 643,976

14 Claims.

(Cl. 42—16)

This invention relates to firearms and more especially to sporting rifles.

An object of this invention is a straight pull breech action rifle provided with positive means to prevent accidental discharge of the rifle.

In a rifle embodying the invention, the breech bolt is slidably mounted in the receiver and carries a locking bolt which swings into a recess in the receiver to lock up the action. The locking bolt carries a pivoted sear which engages the firing pin slidably mounted on the breech bolt either to hold the same against accidental engagement with a cartridge in the chamber or to hold it in cocked position.

15. The rifle is cocked by pulling the firing pin rearwardly, thereby changing the engagement of the sear and firing pin from safety to cocked position and locking the locking bolt in its recess. Pull on the trigger disengages the sear from the firing pin and a spring thrusts the firing pin forward into engagement with the cartridge to fire the same, the locking bolt being at the same time released. The locking bolt is provided with a handle which is pulled straight back to first lift the locking bolt out of its recess into the breech bolt to bring the sear into safety position engagement with the firing pin and then draw back the breech bolt to open the breech and eject the empty shell. On forward movement of the breech bolt to carry a fresh cartridge into the chamber and close the breech, the locking bolt is brought again into its recess with the sear still in safety position engagement with the firing pin. This engagement is broken only upon movement of the firing pin into cocked position and accompanying locking of the locking bolt in its recess.

40. Other objects, novel features and advantages of this invention will be apparent from the following specification and accompanying drawings, wherein:

Fig. 1 is a fragmentary perspective view of a rifle embodying the invention;

45. Fig. 2 is a fragmentary side elevation partly broken away;

Fig. 3 is a vertical section through the receiver;

Fig. 4 is a section on the line 4—4 of Fig. 3;

50. Fig. 5 is a fragmentary perspective view of the breech bolt;

Figs. 6 to 8 inclusive are sections similar to Fig. 3 with the parts in different positions;

Fig. 9 is a section on the line 9—9 of Fig. 3;

55. Fig. 10 is a perspective view partly broken away of the locking bolt, and

Fig. 11 is a perspective view partly broken away of the breech bolt.

The receiver 10 is provided at its front end with a recess in which is received the rear end of the barrel 11 and the receiver, together with

the barrel, are detachably mounted on the stock 12, the stock being grooved to receive the receiver and rear portion of the barrel and a thumb screw 13 being provided to hold the stock and receiver in assembled relation.

5. The receiver 10 is generally cylindrical and is provided with a cartridge receiving and ejecting aperture 14. The breech bolt 15 is of general cylindrical contour and is slidably mounted in the receiver 10. The locking bolt 16 is pivotally carried by the breech bolt and is arranged to swing into and out of a recess in the breech bolt 15. The locking bolt has a pintle portion 17 which is received in a correspondingly shaped transverse groove in the breech bolt to hinge the locking bolt to the breech bolt. The locking bolt carries an arm 18 having a short portion extending parallel to the hinge axis of the breech bolt and a long portion extending generally downward at right angles to the short portion, the long portion terminating in a knob 19. The arm 18 projects through a slot 20 in the breech bolt, this slot being provided at its front end with a shallow notch 21. A lug 15a on the breech bolt extends into the slot 20 and prevents rotation of the breech bolt. 15 At the bottom of the receiver, the wall is cut away to form a recess 22 into which the free end of the locking bolt 16 swings when the breech bolt is in its forward position, the locking bolt in this position preventing rearward movement of the breech bolt. Rearward pull on the knob 19 lifts the locking bolt up out of the recess 22 and into the recess in the breech bolt. 20

25. A firing pin 23 is slidably mounted on the breech bolt 15 and except when in firing position is contained wholly within the breech bolt except for its rear end which extends beyond the rear end of the breech bolt. A spring 24 interposed between shoulders on the firing pin and a plug 25 threaded into the rear end of the breech bolt exerts force on the firing pin tending to move it to firing position. The firing pin is recessed to 30 form a shoulder 26 at the end of an oblique surface 27 and is also provided with a lug 28 having a shoulder 28a arranged in advance of the shoulder 26. The shoulder 26 forms a forwardly facing notch 26a.

35. A sear 29 is pivotally mounted in the locking bolt. A lip 29a at the rear end of the sear is arranged to engage the oblique surface 27 of the firing pin upon upward swing of the locking bolt 16 within its recess to move the firing pin rearwardly until the lip 29a clears the shoulder 26 whereupon the firing pin moves forward slightly to seat the lip 29a in the notch 26a. The sear is also provided with a shoulder 30 which is adapted to engage the shoulder 28 of the firing pin to hold the latter in cocked position. A spring 31 tends to press the rear end of the sear 40 toward the firing pin.

A trigger 32 is pivotally supported in a yoke 33 fastened to the receiver 10. A trigger bar 34 has its rear end lying on the top face of the trigger 32 and has its front end received in a recess 5 in the forward part of the receiver, the forward end of the trigger bar being loosely held in its recess by a stud 35 threaded into the receiver and acting to hold the barrel 11 in place and to receive the thumb screw 13. The trigger bar is provided with an offset 36 which is adapted to engage the front end of the sear 29 to turn the same against the action of the spring 31, upon upward movement of the rear end of the trigger bar 34 effected by pull on the trigger 32.

Fig. 3 discloses the arrangement of the breech bolt, locking bolt, sear, firing pin, trigger and trigger bar directly after firing of the rifle. The rifle is unbreeched and the empty shell ejected by rearward pull on the knob 19. Initial rearward movement of the knob 19 lifts the locking bolt 16 out of the recess 22 and into the breech bolt. During such movement of the locking bolt, the lip 29a rides over the oblique surface 27 thereby retracting the firing pin 23 against the action of the spring 24 until the sear clears the shoulder 26 whereupon the firing pin is moved forwardly until the sear engages the rear face of the notch 26a (Fig. 6). In this relationship of the sear and firing pin, the latter is held short of its firing position. Further pull on the knob 19 draws back the breech bolt (Fig. 7), the empty shell being ejected by means later to be described and the rearward movement of the breech bolt being limited by means later to be described. The rifle is then breeched by forward push on the knob 19 which slides the breech bolt forwardly to its limit of movement and the ultimate movement of the knob 19 swings the locking bolt back again into the recess 22, the rear end of the sear being retained in the notch 26a and holding the firing pin against forward movement into firing position. The rifle is now locked against accidental discharge and the gun may be unbreeched at any time by rearward pull on the knob 19.

The rifle is cocked by drawing the firing pin rearwardly by means of the knob 37 against the action of its spring until the shoulder 28 rides over the shoulder 26 and these two shoulders are brought into locking relationship by the spring 31 in which position the locking bolt is locked in its recess 22 (Fig. 8). Rearward pull on the trigger 32 lifts the rear end of the trigger bar 34, thereby bringing the projection 36 into engagement with the front end of the sear to lift the same and disengage the shoulder 30 from the shoulder 28 of the firing pin, thereby releasing the latter which is thrust forward by its spring 24 into engagement with the cartridge to fire the same (Fig. 3) the sear resuming its position with its rear face in contact with the oblique surface 27.

The front end of the breech bolt is provided with the usual spring actuated extractor 38 which removes the empty shells from the cartridge chamber. The forward lower portion of the breech bolt is cut away to provide a pair of spaced longitudinal ribs 39 and between these ribs is arranged the ejector 40 which, as the breech bolt is drawn back, engages the empty shell carried by the extractor to flip the shell out through the aperture 14. The ejector constitutes the inner end of a member projecting through a slot in the bottom of the receiver, and having a base 41 exterior of the receiver, the base having a nib received in a depression in the outer wall of the

receiver to fulcrum the ejector. A spring 42 is arranged between the trigger bar 34 and the ejector and presses the ejector inwardly. The ribs 39 are cut out to form shoulders 43 and the extractor is provided with shoulders 44 which, when the breech bolt is retracted, are pressed by the spring 42 into engagement with the shoulders 43 to limit the rearward movement of the breech bolt, the ejector at such time being clear of the front end of the bolt to permit the required movement of the ejector. The ejector thus serves as the breech bolt stop. When the breech bolt is in its forward position, the ejector is forced downwardly against the action of the spring 42 as shown in Fig. 6 and when the breech bolt is in its rear position, the spring 42 forces the ejector into the position shown in Fig. 7 in which position it prevents further retraction of the breech bolt.

A cartridge guide 45 is provided in the bottom of the receiver. This cartridge guide is grooved to receive a cartridge and has a portion extending through the same slot in the bottom of the receiver as the ejector. A spring 46 underlies the front end of the guide and the guide is tiltably supported at its rear end, the spring 46 tending to hold the guide in the position shown in Fig. 7 when the breech bolt is retracted. The lower portion of the cartridge guide is provided with a recess 45a into which extends a projection 34a on the trigger bar 34, this arrangement permitting tilting movement of the guide. Upon forward movement of the breech bolt, it pushes the cartridge from the guide into the chamber and swings the guide into the position shown in Fig. 8. Additional safety means are provided for locking the firing pin in cocked position. The knob 37 is rotatably mounted on the end of the firing pin and is provided with a longitudinal groove 47 which normally registers with a pin 48 carried by the plug 25. When the firing pin has been pulled back to cocked position, the knob 37 may be rotated a portion of a turn, thus moving the groove 47 out of register with the pin 48, thereby preventing forward movement of the firing pin.

After the firing pin has been set in cocked position, it can be returned to safety position by pulling the trigger while at the same time holding the firing pin and letting it go forward slowly. Under such conditions, the sear will be elevated to bring the lip 29a into alignment with the notch 26a and prevent movement of the firing pin into firing position.

The breech bolt assembly may be removed from the receiver by simultaneously pulling on the trigger and the knob 19. Pull on the trigger with the breech bolt retracted causes the ejector to be disposed to such extent that the shoulders 44 are held out of engagement with the shoulders 43, this position of the ejector being effected by engagement of the trigger bar with the free end of the ejector.

It is of course to be understood that various modifications may be made in the structure above described, without in any way departing from the spirit of the invention as defined in the appended claims.

I claim:

1. In a firearm, a receiver, a non-rotatable cylindrical breech bolt slidably mounted in said receiver, a locking bolt pivotally carried by said breech bolt and adapted to be contained within said breech bolt, said receiver having a slot into which said locking bolt projects when in locking position, and means bodily translatable parallel to the direction of movement of said breech bolt

for actuating said locking bolt and reciprocating said breech bolt.

2. In a firearm, a receiver, a cylindrical breech bolt slidably mounted in said receiver, means preventing rotation of said breech bolt, a locking bolt pivoted to said breech bolt and adapted to be contained within said breech bolt, said receiver having a slot into which said locking bolt projects when in locking position, and means bodily 5 translatable parallel to the direction of movement of said breech bolt for swinging said locking bolt and reciprocating said breech bolt.

3. In a firearm, a receiver having a longitudinal slot, a cylindrical breech bolt slidably mounted in said receiver, a locking bolt pivoted to said breech bolt and adapted to be contained within said breech bolt, said receiver having a slot into which said locking bolt projects when in locking position, and an arm carried by said 10 locking bolt, said arm being bodily translatable parallel to the direction of movement of said breech bolt and having a portion parallel to the axis of said locking bolt and a second portion perpendicular to said first portion, said arm being operable by pull on the end thereof parallel to the direction of movement of said breech bolt to actuate said locking bolt and reciprocate said 15 breech bolt.

4. In a firearm, a receiver having a longitudinal slot, a breech bolt slidably mounted in said receiver, a locking bolt pivoted to said breech bolt, an arm carried by said locking bolt, said arm projecting through said slot, a firing pin slidably mounted on said breech bolt, a sear pivotally mounted on said locking bolt, inter-engaging means on said sear and firing pin to hold the latter in cocked position, and trigger means for 20 disengaging said sear from said firing pin.

5. In a firearm, a receiver having a longitudinal slot, a breech bolt slidably mounted in said receiver, a locking bolt pivoted to said breech bolt, an arm carried by said locking bolt, said arm projecting through said slot, a firing pin slidably mounted on said breech bolt, a forwardly facing 25 notch in said firing pin, a sear pivotally mounted on said locking bolt, means on said sear engaging said notch to prevent movement of the firing pin into firing position, additional inter-engaging means on said sear and firing pin for holding the 30 firing pin in cocked position, said first named means being rendered inoperative upon movement of the firing pin into cocked position.

6. In a firearm, a receiver, a breech bolt slidably mounted in said receiver, a locking bolt pivoted to said breech bolt, a sear pivotally mounted on said locking bolt, a forwardly facing notch in said firing pin, and means on said sear engaging said notch to prevent movement of the firing pin into firing position.

60 7. In a firearm, a receiver, a breech bolt slidably mounted in said receiver, a locking bolt pivoted to said breech bolt, a firing pin slidably mounted on said breech bolt, a sear pivotally mounted on said locking bolt, inter-engaging means on said sear and firing pin, a trigger bar pivoted at one end to the receiver and having means engageable with said sear, and a trigger engaging the free end of said bar to lift the same into engagement with the sear.

70 8. In a firearm, a receiver, a breech bolt slidably mounted in said receiver, a locking bolt pivoted to said breech bolt, a firing pin slidably mounted on said breech bolt, a sear pivotally

mounted on said locking bolt, inter-engaging means on said sear and firing pin to prevent movement of the firing pin into firing position, additional inter-engaging means on said sear and firing pin for holding the firing pin in cocked position, said first named means being rendered inoperative upon movement of the firing pin into cocked position.

9. In a firearm, a receiver having a longitudinal slot, a breech bolt slidably mounted in said receiver, a locking bolt pivoted to said breech bolt, a recess in the receiver to receive the free end of said locking bolt, an arm carried by said locking bolt and projecting through said slot, a spring actuated firing pin slidably mounted on said breech bolt, a sear pivotally mounted on said locking bolt, inter-engaging means on said sear and firing pin for preventing movement of the firing pin into firing position, additional inter-engaging means on said sear and firing pin for holding the latter 10 in cocked position, said first named means being rendered inoperative upon movement of the firing pin into cocked position, a trigger bar pivoted at one end to the receiver and being engageable with said sear to disengage the same from the firing 15 pin, and a trigger engaging the free end of said bar to lift the same into engagement with said sear.

10. In a firearm, a receiver having a bottom slot, a breech bolt slidably mounted in said receiver, an ejector comprising a base portion loosely fulcrumed in the outer wall of the receiver, and a shell engaging portion extending through said slot into the receiver, and spring means pressing said ejector inwardly of the receiver and 20 constituting the sole means for holding the ejector in position.

11. In a firearm, a receiver having a bottom slot, a breech bolt slidably mounted in said receiver, an ejector comprising a base portion 25 loosely fulcrumed in the outer wall of the receiver, a shell engaging portion extending through said slot into the receiver, spring means pressing said ejector inwardly of the receiver and constituting the sole means for holding the ejector in 30 position, and inter-engaging shoulders on said breech bolt and ejector for limiting rearward movement of the breech bolt.

12. In a firearm, a receiver having a bottom slot, a breech bolt slidably mounted in said receiver, an ejector comprising a base portion engaging the outer wall of the receiver, a shell engaging portion extending through said slot into the receiver, a pivoted trigger bar, and a spring 35 interposed between said trigger bar and ejector.

13. In a firearm, a receiver having a bottom slot, a breech bolt slidably mounted in said receiver, an ejector comprising a base portion engaging the outer wall of the receiver, a shell engaging portion extending through said slot into the receiver, a pivoted trigger bar, a spring interposed between said trigger bar and ejector, and inter-engaging shoulders on said breech bolt and ejector for limiting rearward movement of the 40 breech bolt.

14. In a firearm, a receiver having a bottom slot, a cartridge guide resting on the bottom of said receiver and having a portion extending through said slot, a spring underlying the front end of the guide, a pivoted trigger bar, and means 45 on said trigger bar engaging said extending portion to constitute a fulcrum for said guide.

CARL G. SWEBILIUS.
